UNITED STATES PATENT OFFICE.

ARTHUR PELLOW, OF SOUTHBRIIDGE, MASSACHUSETTS, ASSIGNOR TO AMERICAN OPTICAL COMPANY, OF SOUTHBRIIDGE, MASSACHUSETTS, A VOLUNTARY ASSOCIATION OF MASSACHUSETTS.

LENS.

Application filed April 4, 1921. Serial No. 458,242.

To all whom it may concern:

Be it known that I, ARTHUR PELLOW, a citizen of the United States, residing at Southbridge, in the county of Worcester and State of Massachusetts, have invented certain new and useful Improvements in Lenses, of which the following is a specification.

This invention relates to improvements in lenses and has particular reference to blanks for use in the production of ophthalmic lenses.

Prior to the present invention difficulties have been experienced in connection with the molding of ophthalmic lens blanks due to the formation of a slight fin or ridge about the edge of the blank. It is, therefore, one of the primary purposes of the present invention to provide a novel and improved blank construction which shall eliminate the difficulties hitherto experienced on account of the formation of such fin.

A further object of the present invention is the provision of a novel and improved construction which shall make it possible to eliminate preliminary treating of the blank before grinding, which shall insure proper engagement between the grinding tool and blank when being ground and eliminate all liability of chipping of the blank at the edges.

Other objects and advantages of my improved construction should be readily apparent by reference to the following specification taken in connection with the accompanying drawings, and it will be understood that I may make any modifications in the specific features hereinafter disclosed within the scope of the appended claims without departing from or exceeding the spirit of my invention.

Figure I represents a plan view of a blank embodying my improvements.

Figure II represents a sectional view of a prior art construction.

Figure III represents a similar view showing a subsequent step in the production of such prior art construction.

Figure IV illustrates the moulding of a prior art blank.

Figure V represents a sectional view through my improved blank.

Figure VI is a sectional view illustrating the use of my blank.

Figure VII represents a plan view of a slightly modified construction.

Prior to my invention it has been customary to produce blanks for the manufacture of ophthalmic lenses by moulding the glass substantially to the desired form, thus reducing to a minimum the subsequent grinding necessary. Difficulties, however, have been experienced due to the fact that the edge of the mold plunger 1 tends to wear slightly as at 2, so that as it presses against the glass stock 3 in the mold 4 a slight fin 5 is formed around the edge of the blank. This fin is objectional since while of relatively thin formation it tends if broken off to break down an adjacent portion of the glass rendering it liable to chip, and prevents the blank properly fitting on the grinding tool for initial grinding, rendering the edge liable to be broken as the grinding starts, entailing the possibility of slightly tilted grinding, and introducing certain prismatic effect in the lens. It has hitherto been necessary to bevel off the edge as indicated at 6 in Figure III, this result ordinarily being accomplished by the lens being held by hand against the edge of a rotating stone which will grind down the rib 5. This, of course, adds considerable to the cost of production of the blanks and is a relatively unnecessary operation.

I have, therefore, provided my improvement in structures of this character, which consists in molding on the face of the blank spaced inwardly somewhat from the edge the annular rib 7, as shown in Figure V, or the series of projections 8 as shown in Figure VII, the two being substantially equivalents, in that in either event the projections are high enough so that they will contact with the grinding tool 9 before the fin comes into engagement with the tool so that the initial grinding is a grinding away of these projections 7 or 8, which while a relatively rapid process is sufficiently slow to allow of the fin being evenly ground off and without danger of breakage, as would be the case were the pressure of the grinding operation all exerted against the uneven fin.

By my improved construction, therefore, I provide a blank making it unnecessary to first edge or chamfer the molded blank, and also provide the rim 7 or steadyng projections 8, which are so spaced and related that

they will correctly position the blank on the block without tilting and will allow the blank to move down gradually into engagement with the grinding tool so that all inequalities produced by moulding are properly removed and liability of incorrect tilting and production of prism in the finished lens on account of tilting reduced to a minimum.

I claim:

- 10 1. As an article of manufacture, a lens blank having integral means formed on the face thereof for initial engagement with a grinding tool, said means being disposed intermediate the center and edge of the lens and positioned to balance the lens on the grinding tool at the start of the grinding operation.
- 15 2. As an article of manufacture, a lens blank having near the edge thereof a portion projecting from the face of the blank for engagement with the grinding tool face prior to engagement between the grinding tool face and an annular fin which forms on the edge of the lens when molded, whereby
- 20 25 the blank may balance on the grinding tool face at the start of the grinding operation.

3. As an article of manufacture, a moulded blank having on its face an integral annular rib spaced inwardly from and substantially conforming to a fin, which forms on the lens edge when molding the lens, the construction and arrangement of the rib being such as to balance a lens on the grinding tool face.

4. As an article of manufacture, a molded lens blank provided with means integral with one face of the lens and located intermediate the center and edge of the lens, the construction and arrangement of said means being such that it may contact with the grinding tool face prior to engagement between the grinding tool face and a fin which usually forms on the lens blank when molding the same, thereby acting to balance a blank on the grinding tool face.

In testimony whereof I have affixed my signature, in presence of two witnesses.

ARTHUR PELLOW.
